UNITED STATES PATENT OFFICE.

JOHN T. CURRAN, OF BROOKLYN, ASSIGNOR TO TIFFANY & CO., OF NEW YORK, N. Y.

DESIGN FOR A KNIFE.

SPECIFICATION forming part of Design No. 23,034, dated February 6, 1894.

Application filed August 28, 1893. Serial No. 484,236. Term of patent 7 years.

To all whom it may concern:

Be it known that I, JOHN T. CURRAN, a citizen of the United States, residing at Brooklyn, Kings county, State of New York, have ⁵ invented a new and original Design for Knives, of which the following is a specification.

In the drawing is shown a blade and handle united to form a knife complete and embodying both parts of my design.

The leading features of my invention comprise a knife blade having the line of its back sloping gently upward from the point and having a band of ornamental lines and scrolls ¹⁵ on the back of the blade extending from the hilt toward the middle thereof and gradually decreasing in width toward the point; they also comprise a handle having an ornamental band of longitudinal wavy lines and branching volute lines.

The blade of the knife has the line of its cutting edge curved gently upward toward the point at *a*. The line of the back of the knife has a slight depression near the point ²⁵ at *b*, and gradually diverges from the line of the cutting edge toward the point *c*, from which point it gradually approaches the cutting edge. From the point *c* toward the handle there is on the back of the blade a band ³⁰ of ornamentation gradually increasing in

width, consisting of the curved lines *d* and the volute lines *e*, giving a vermiciform appearance and making the contour of the back of the blade from the point *c* backward scalloped.

The handle consists of the portions *f* and *g*. The portion *f* has a series of transverse lines *f'*, giving the appearance of several folds, which surround the portion *f*. The part *g* has its contour on its upper side substantially even, but on its lower side it is scalloped at *h*, and the elevations at the crests of the scallops run down the side of the handle. Along the middle of the handle are a series of longitudinal wavy lines *k* having ⁴⁵ branching volute lines *k'*, these terminate in the ornamental volute lines *m* running diagonally toward the lower outer end of the handle. ⁵⁰

What I claim as new is—

1. In the design for a knife, the blade substantially as shown.
2. In the design for a knife, the handle substantially as shown.
3. The design for a knife consisting of the design substantially as shown.

JOHN T. CURRAN.
